(57) **CLAIM**

The ornamental design for a motorcycle tire, as shown and described.

DESCRIPTION

FIG. 1 is a perspective view of a motorcycle tire according to my design;

FIG. 2 is a front view thereof;

FIG. 3 is a top view thereof;

FIG. 4 is a right side view thereof;

FIG. 5 is a fragmentary enlarged front view showing the details of the tread portion thereof;

FIG. 6 is a section view taken along line 6-6 in FIG. 5;

FIG. 7 is a section view taken along line 7-7 in FIG. 5; and,
 FIG. 8 is a fragmentary enlarged perspective view showing the details of the tread portion thereof.

The broken lines are for the purpose of showing environmental structure only and form no part of the claimed design.
